United States Patent Office.

W. F. DAUGHERTY, OF MOUNT PLEASANT, IOWA.

Letters Patent No. 69,779, dated October 15, 1867.

IMPROVED BED-BOTTOM.

The Schedule referred to in these Letters Patent and making part of the same.

TO ALL WHOM IT MAY CONCERN:

Be it known that I, W. F. DAUGHERTY, of Mount Pleasant, in the county of Henry, and in the State of Iowa, have invented a new and useful improvement in Bed-Springs; and I do hereby declare that the following is a full, clear, and exact description thereof, reference being had to the accompanying drawings, and to the letters of reference marked thereon, in which—

Figure 1 is a plan view, and,

Figure 2 is a side elevation.

The nature of my invention consists in the manner of attaching the springs to the cross-bars, and of letting said cross-bar, into the additional side rails, and of inserting a link between the spring and the catch-hook on the ends of the spring-bars, as hereinafter fully described.

To enable others skilled in the art to make and use my invention, I will proceed to describe its construction and operation.

In the construction of my invention, in fig. 1, A the additional side rail, which has a socket cut into it, as seen at *a a a a* in said figure, and which rail is firmly screwed, by four screws at each end, to the side rail of the bedstead. The spring-bar or cross-bar is B B, through which the lower projecting ends of the springs C C pass, and which are turned over at right angles, on the lower side of the said bar, and clinched, and in the rear or outside of it, thus giving rigidity to the position of the spring. The springs are regularly coiled, as is common to springs of this class, through which passes a rod, D D, which rod rests on blocks *b b*, resting on spring-bars B B, and which all combine to keep the springs securely in their place. The upper and inner ends of the springs rise, inclining inward, about two-thirds the length of the spring, and to which is attached the clevis part of the spring E E, and is, on its inner-face side, attached to a hook, *c c*, firmly riveted to the under side of the spring-bars or bed-bottom *d d d d*. When the bottom is thus constructed, the cross-bars B B are pushed down into the sockets *a a a a* in the side rail A A, where it fits snugly and firmly, and is now ready for use.

In the operation of my invention, it will be seen that, from the manner in which my springs are coiled and braced, the pressure is equally distributed through the whole spring, and it cannot rise or become deranged in its operation. It will be further seen that, by means of the clevis, a greatly improved motion is given to the spring-bottom. As the pressure is placed on the bottom, the clevis is pressed down, if sufficient weight be applied, to a vertical position, thus causing the bottom to sink equally the whole length of the slat, thus giving a regular motion to the bed-bottom. By the addition of the clevis I am enabled to give an easy, regular motion to the entire bottom. Also, by the use of the clevis and hook, I can with ease attach and detach the bottom or any part of the same.

Having thus fully described the construction and operation of my invention, what I claim as new, and desire to secure by Letters Patent, is—

The clevis E, as constructed and arranged, in combination with the spring C and hook *c*, substantially as described, and operating as set forth.

In testimony that I claim the above-described improvement in bed-springs, I have hereunto signed my name this 22d day of August, 1867.

W. F. DAUGHERTY.
